LOCKING TYPE HAIR-WAVING ROD

Roy F. Burch, Sr., Denver, Colo.

Application August 8, 1947, Serial No. 767,481

6 Claims. (Cl. 132—41)

1

This invention relates to improvements in hair curling devices and more particularly to devices of the type disclosed in my Patent No. 2,421,008 of May 27, 1947, which are intended for use in the cold set or roller method of hair curling.

In the usual cold set method of hair curling, the hair ends become unset and loosely curled sooner than the main body of the roll, thereby necessitating a resetting of the entire coiffure. Also, the conventional type of rollers may be fixed only in positions along the hair length a half or full revolution apart, and when held close to the scalp, will draw the hair so tightly as to cause extreme discomfort, while the next position will leave a slight uncurled length of hair.

While the device of my prior patent overcame these difficulties, it relied solely on the retractable U-shaped wire member for its locking function, while the finger member which clamps against the main portion of the curl was not held in a fixed position and could work loose on the curl.

It is a primary object of this invention to provide a cold set hair curler which produces more tightly coiled hair ends than in the remaining length, thereby increasing the effectiveness of the treatment.

Another object of the invention is to provide a positive locking arrangement in a hair curler of the cold set type, which effectively holds both the finger portion and the wire clamp of such a curler against movement.

A further object of the invention is to provide a positive locking arrangement which permits fixing such a curler in adjustable and selective positions along a strand of hair.

Other objects reside in novel details of construction and novel combinations and arrangements of parts, all of which will be described in the course of the following description.

In the drawings, in which like parts have been designated similarly,

Fig. 1 is a perspective view of a hair curler embodying features of the present invention, and showing the position of the hair strand by dotted line representation;

Fig. 2 is a side elevation of the curler shown in Fig. 1 with the retracted positions of the mechanism and the hair strand position indicated by dotted line representation; and

Fig. 3 is a developed section taken along the line 3—3, Fig. 2.

Before describing the details of the present invention, it is to be understood that the inven-

2

tion is not limited in its application to the details of construction and arrangement of parts illustrated in the accompanying drawing, since the invention is capable of other embodiments and of being practiced in various ways. It is to be further understood that the terminology employed herein is for purposes of description and not in limitation, as it is not intended to limit the invention except as set forth in the appended claims.

10. The curler shown in the drawing preferably comprises a tubular body portion 4, the cross section of which progressively narrows from a point adjacent its respective ends 5 and 6 to a central point, and has at intervals throughout its length a series of apertures 7. A recess 8 is provided at end 6 to receive an extension on a finger member 9 which is folded back upon itself to provide a pivotal attachment of the member on the body as shown at 10.

15. The finger member 9 has its greatest width adjoining pivot 10 and terminates at each side in at least one and preferably two rolled portions adapted to function as sockets 12 for the reception of a locking wire 13, generally of U-shape and preferably having the outer ends of its leg portions flattened as shown at 14 (Fig. 2) to prevent withdrawal through the socket members 12 after once assembled. Preferably, finger 20 member 9 conforms in contour to the external shape of body 4 so that it will lie flat against said body throughout its length, and a series of apertures 15 are provided in finger 9.

The cross connecting portion of wire 13 extends laterally from the leg portions and then loops in U or V formation 16 so that the lateral portions 17 function as a stop to engage the end 6 of body 4 while the loop 16 acts as a pull for manipulation of the wire in the manner to be 25 subsequently described. At least one or preferably two shoulders 18 (as shown) are formed on the end 6 of the body portion to provide a rest for pull 16 when wire 13 is in its normally retracted position.

30. In the use of the device hereinbefore described, wire 13 is drawn from its completely retracted position a distance sufficient to move pull 16 out of contact with shoulders 18, thus permitting the wire to be used in rotating finger 9 so as to move it from the full line position to the dotted line position shown in Fig. 2. A strand of hair suitably treated with wave solution or otherwise prepared for curling is wound about body 4 and may be drawn as tightly as desired, after which finger 35 9 is moved to the reclining position overhanging

body 4 and the wire 13 is then moved into its retracted position with the pull 16 seated on shoulders 18 as illustrated in Fig. 2, in which position the rotation of finger 9 about pivot 10 is prevented by the aforesaid engagement of the pull with the shoulders. In this position, the leg portions of wire 13 also hold the outer surface of the wound strand in position and it is allowed to remain until the curl is sufficiently set to permit removal of the device. The provision of the holes 7 in body 4 and 15 in finger 9 insures sufficient air circulation through the body and finger portions while the unit is holding the strand to permit rapid drying and evaporation of contained moisture.

Due to the clamping action of finger 9 when the wire is in its retracted position, the tightly wound strand is prevented from slipping as frequently occurs in the use of devices of this general character. Despite this positive gripping action, the manner of fastening the strand in position insures against undue pulling or twisting which would be a source of discomfort to the user.

Devices made in accordance with the structure shown and described may be formed of any suitable material, such as plastic, metal or the like. I have found that a die-cast aluminum construction is particularly desirable because of the light weight of the assembled device and the low cost of manufacture. Preferably, the wire 13 will be steel stock.

What I claim and desire to secure by Letters Patent is:

1. A device of the character described, comprising an elongated body having a shouldered surface at one of its ends, clamping means pivotally attached to said body adjacent the shouldered end for rotation through substantially ninety degrees and normally extending longitudinally of said body in closely overhanging relation thereto so as to thereby hold a coil of hair wound about the body against slippage, and a U-shaped member having legs slidably mounted in socket-forming surfaces of the clamping means for pivotal movement therewith and extending into spaced superposed relation with the body so that the legs of said member will hold other convolutions wound about said coil and said clamping means, and said U-shaped member having a portion engaging the shouldered surface of the body to arrest the pivotal movement of said clamping means when the U-shaped member is in said superposed position.

2. A device of the character described, comprising an elongated body having a shouldered surface at one of its ends, clamping means pivotally attached to said body adjacent the shouldered end for rotation through substantially ninety degrees and normally extending longitudinally of said body in closely overhanging relation thereto so as to thereby hold a coil of hair wound about the body against slippage, and a U-shaped member having legs slidably mounted in socket-forming surfaces of the clamping means for pivotal movement therewith and extending into spaced superposed relation with the body so that the legs of said member will hold other convolutions wound about said coil and said clamping means, and said U-shaped member having an extension portion providing a pull and engaging the shouldered surface of the body to arrest the pivotal movement of said clamping means when the U-shaped member is in said superposed position.

3. A device of the character described, comprising an elongated body having a shouldered surface at one of its ends, clamping means pivotally attached to said body adjacent the shouldered end for rotation through substantially ninety degrees and normally extending longitudinally of said body in closely overhanging relation thereto so as to thereby hold a coil of hair wound about the body against slippage, and a U-shaped member having legs slidably mounted in socket-forming surfaces of the clamping means for pivotal movement therewith and extending into spaced superposed relation with the body so that the legs of said member will hold other convolutions wound about said coil and said clamping means, and said U-shaped member having a portion interconnecting said legs and arranged to engage the shouldered surface of the body to arrest the pivotal movement of said clamping means when the U-shaped member is in said superposed position.

4. A device of the character described, comprising a hollow elongated body having two spaced projections at one of its ends and an opening in said end spaced from the projections, clamping means pivotally attached to said body through the opening in said end and normally extending longitudinally of said body in closely overhanging relation thereto so as to thereby hold a coil of hair wound about the body against slippage, and a U-shaped member having legs slidably mounted in socket-forming surfaces of the clamping means and extending into spaced superposed relation with the body so that the legs of said member will hold other convolutions wound about said coil and said clamping means, and said U-shaped member having a portion engaging the projections at the end of the body to arrest the pivotal movement of said clamping means when the U-shaped member is in said superposed position.

5. A device of the character described, comprising an elongated body having a shouldered surface at one of its ends, clamping means pivotally attached to said body and normally extending longitudinally of said body in closely overhanging relation thereto so as to thereby hold a coil of hair wound about the body against slippage, and a U-shaped member having legs slidably mounted in socket-forming surfaces of the clamping means and extending substantially parallel with the lengthwise axis of the body into spaced superposed relation with the body so that the legs of said member will hold other convolutions wound about said coil and said clamping means, the ends of said legs being widened to prevent entry into said sockets, and said U-shaped member having a portion engaging the shouldered surface of the body to arrest the pivotal movement of said clamping means when the U-shaped member is in said superposed position.

6. A device of the character described, comprising a tubular, open-ended body having a shoulder extension at one of its ends and of greater diameter at its ends than in its intermediate portion, there being a recess in the shouldered end of said body, an elongated clamping member having a looped portion at one end extending through said recess and folded to provide a pivotal connection with the body, said member throughout its length conforming to the contour of said body and normally being positioned to closely overhang said body so as to thereby hold a coil of hair wound about the narrow diameter of the body against slippage, said member hav-

ing side portions formed into spaced parallel sockets, and a U-shaped member having a U-shaped interconnecting portion and legs extending through said sockets in superposed relation to the body for holding other convolutions wound about said coil and said clamping means, said U-shaped interconnecting member being arranged to engage the shouldered end of the body when the legs are in said superposed position so as to resist any pivotal movement of said clamping member.
